UNITED STATES PATENT OFFICE.

MAX F. WERNER, OF MADISON, WISCONSIN, ASSIGNOR OF ONE-HALF TO EDWIN L. FOSS, OF MADISON, WISCONSIN.

WATER-ELEVATING DEVICE.

Application filed October 26, 1921. Serial No. 510,439.

To all whom it may concern:

Be it known that I, MAX F. WERNER, a citizen of the United States, residing at Madison, in the county of Dane and State 5 of Wisconsin, have invented certain new and useful Improvements in Water-Elevating Devices, of which the following is a specification.

This invention relates to apparatus for 10 elevating water, more particularly to devices for elevating water from confined spaces such as driven or artesian wells, and has for one of its objects to provide a simply constructed apparatus whereby the force required to elevate the water is reduced without materially increasing the weight or expense of manufacture.

With these and other objects in view the invention consists in certain novel features 20 of construction as hereinafter shown and described and then specifically pointed out in the claims, and in the drawings illustrative of the preferred embodiment of the invention:—

25 Figure 1 is a vertical sectional elevation, Figure 2 is an enlarged transverse section on the line 2—2 of Figure 1, Figure 3 is a side view, partly in section, 30 of a portion of the suction tube of the improved apparatus.

The improved device is designed more particularly for use in connection with driven or artesian wells wherein the water is confined within relatively narrow limits, 35 such as a well tube or the like, and for the purpose of illustration is shown thus applied, the well tube being represented at 10 of the usual construction.

Supported within the casing 10 is a tube 40 11 smaller than the casing with its lower end open and constantly immersed thereby in the water in the casing and with a pump tube indicated at 12 at the upper end.

Disposed within the tubular member 11 45 and extending below the same, preferably to the bottom of the casing 10, is a displacing member 13, preferably tubular, and plugged at the lower end as shown at 14.

Spacer devices 15 are disposed between 50 the casing 10 and the tubular member 11 while similar spacer devices 16 are disposed between the tubular member 11 and the displacing member 13.

By this means the tubular member 11 is 55 supported in constant parallel relation to the

casing 10, while the water displacing member 13 is maintained in constant spaced relation relative to the tubular member 11.

At its upper end the casing 10 is shown supported by an annular plate or flange 18, 60 and supported by the flange and also by the upper end of the casing is a cap device 19, the latter also supporting the pump tube 12.

The water naturally stands at a certain 65 level within the casing 10 and suction tube 13 as indicated at 20, and the tubular member 11 is of sufficient length to maintain its lower open end constantly immersed for a considerable portion of its length in the 70 water.

When the displacer member is inserted the water will be caused to rise in the suction tube and in the well tube to an extent equal to the bulk of the displacing member. 75 By this means the pumping action is materially improved and the force required to elevate the water correspondingly reduced, as the "lift" of the pump is materially reduced and the water to be elevated 80 constantly maintained at a substantially uniform level in the confined space between the members 11 and 13, and 10 and 11.

It will be understood that the suction distance of the pump will be within the theoretical distance value.

The operation requires the same power as it would by any high power pump at first, but after a few hard strokes of the pump, or after the "suction" is started, it will take 90 less and less power until it is reduced to one fourth of its strength, or still less, depending on how strong the inflow of water is at the bottom. If the inflow be very strong the water will flow almost freely itself so 95 long as a little suction is kept up.

The suction tube 11 must always be about 10 to 16 feet below the original water line, so that the suction pipe never will fail, especially in wells of certain depths.

The improved device is simple in construction, can be inexpensively manufactured and of any size or capacity, and of any suitable material.

The preferred embodiment of the invention is disclosed in the drawings and set forth in the specification, but it will be understood that modifications within the scope of the claimed invention may be made in the construction without departing from the 105 110

principle of the invention or sacrificing any of its advantages.

Having thus described the invention what is claimed as new is:—

- 5 1. An apparatus of the class described comprising a suction tube adapted to be supported in a well tube with its lower end constantly below the water line therein and of less diameter than the well tube, and a 10 displacing member of less diameter than the suction tube and extending through the same and to the bottom of the well and operating to elevate the water in the suction tube and in the well tube to an extent equal to 15 the displacement of the displacing member, said suction tube adapted to be connected to a pumping appliance.
- 15 2. An apparatus of the class described

comprising a suction tube adapted to be supported in a well tube with its lower end 20 constantly below the water line therein and of less diameter than the well tube; a displacing member of less diameter than the suction tube and extending to the bottom of the well and operating to elevate the water 25 in the suction tube and in the well tube to an extent equal to the displacement of the displacing member, and means carried by the suction tube for supporting the same and the displacing member in spaced relation to 30 each other and to the well tube, said suction tube adapted to be connected to a pumping appliance.

In testimony whereof, I affix my signature hereto.

MAX F. WERNER.
